(57) **CLAIM**

The ornamental design for a connector interface, as shown and described.

DESCRIPTION

This application is filed concurrently with U.S. Design application Ser. No. 29/533,825, entitled "Watch Body", which is incorporated herein by reference in its entirety.

FIG. 1 is a plan view showing a connector interface according to our new design;

FIG. 2 is a perspective view thereof;

FIG. 3 is a plan view of the connector interface shown on a watch body; and,

FIG. 4 is a perspective view thereof.

The broken line showing in FIGS. 1-4 immediately adjacent shading forms a boundary of the claimed design. The watch body is shown in broken lines in FIGS. 3-4 for environmental purposes only and forms no part of the claimed design.
